(57) **CLAIM**

The ornamental design for a reversing camera mounting bracket, as shown and described.

DESCRIPTION

FIG. 1 is a perspective view of a reversing camera mounting bracket showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 shows the reversing camera mounting bracket of my design with a camera mounted thereon.

The broken line showing of a camera and partial cord is included for the purpose of illustrating environment and forms no part of the claimed design.
